UNITED STATES PATENT OFFICE.

JUNIUS H. DAVIS, OF PHILADELPHIA, PENNSYLVANIA.

DESIGN FOR THE ORNAMENTATION OF A SPOON, FORK, OR KNIFE HANDLE.

SPECIFICATION forming part of **Design No. 18,459**, dated **July 17, 1888**.

Application filed April 12, 1888. Serial No. 270,484. Term of patent 7 years.

To all whom it may concern:

Be it known that I, JUNIUS H. DAVIS, a citizen of the United States, and a resident of Philadelphia, Pennsylvania, have invented a new and original Design for the Ornamentation of a Spoon, Fork, or Knife Handle, of which the following is a specification.

My design for the ornamentation of a spoon, fork, or knife handle is fully illustrated in the accompanying drawings, in which—

Figure 1 is a face view of the complete handle, and Fig. 2 a similar view of the outer portion or head of the handle.

The design comprises a series of fan-like scrolls, A, radiating from a common center, a, near the outer end of the handle, the innermost fan-like scroll terminating in a foliated scroll design, which extends along the shank B of the handle to the base of the same. A spray, D, of small flowers or blossoms extends diagonally across the fan-like scrolls from one

edge of the handle, and along the other edge of the handle is a series of circular projections, b.

The special and distinctive feature of my invention is the ornamentation of the outer portion or head of the handle, and this design is therefore shown detached in Fig. 2.

I claim—

A design for the ornamentation of a spoon, fork, or knife handle, said design consisting of the fan-like scrolls A and the floral spray D, extending diagonally across the same, all substantially as described and shown.

In testimony whereof I have signed my name to this specification in the presence of two subscribing witnesses.

JUNIUS H. DAVIS.
